United States Patent Office.

JAMES D. BRYSON AND J. H. HARTSUFF, OF NEWCASTLE, PENNSYLVANIA.

Letters Patent No. 97,869, dated December 14, 1869.

IMPROVEMENT IN WATER-WHEELS.

The Schedule referred to in these Letters Patent and making part of the same.

To all whom it may concern:

Be it known that we, JAMES D. BRYSON and J. H. HARTSUFF, of Newcastle, in the State of Pennsylvania, have invented a new and useful Improvement in Casings for Turbine Water-Wheels; and we do hereby declare that the following is a full, clear, and exact description of the same, reference being had to the accompanying drawings, and letters of reference marked thereon, making a part of this specification, in which—

Figure 1 is a plan view, a portion of the upper ring being broken away.

This invention has for its object the introduction to a water-wheel of the greatest possible amount of water that can economically be used by it.

We seek to accomplish this end by dispensing with a curb altogether, and placing nothing around the periphery of the wheel but chutes and gates.

To enable those skilled in the art to make and use our invention, we now proceed to describe its construction and operation.

Similar letters, in the drawings, refer to like parts. The invention consists in pivoting the gates, by means of trunnions projecting from their upper and lower edges, to sliding rings placed outside of stationary rings, the latter being attached to the upper and lower edges of the chutes, and the sliding of the former being effected by any suitable mechanical appliances; the gates being so placed, with reference to the chutes, that when open, they lie close alongside the latter, so as to interpose only the combined thickness of the two as an obstacle to the water; the outer ends of the gates and chutes being made sharp, and their sides being perfectly smooth; the gates having greater superficial surface outside of than within the trunnions, in order that the pressure of the water may keep their outer ends always in contact with the chutes, and thus out of the way of the water when the gates are open, and affording no crevice to the water when the gates are closed; the chutes having straight sides, and the gates being convex as to the chutes throughout their entire surface, so as to avoid corners, which more or less hinder the water's flow; each gate having an independent as well as a concurrent motion, so that an obstruction to the closing of one does not affect the operation of its fellows.

In the drawings—

A is the crown-plate, to the under side of which, and flush with its periphery, is bolted a ring, (not shown,) next which is the inner edge of the upper sliding ring a, resting on the columns a'.

The lower sliding ring a' is connected with the upper one by said columns, and has an inner ring to turn on,

placed in a groove in the bed-plate of the casing, immediately beneath the upper inner ring.

The chutes b are cast in connection with the two inner rings, and are placed, with reference to each other, on the familiar principle of affording gradually-contracted veins for the influx of water.

The chutes are chamfered at their ends to facilitate the entrance and exit of water to and from the veins.

The rings a a' slide, through the operation of the usual vertical gear-post c, meshing with series of teeth in the outer edges of the rings.

The gates d are pivoted vertically to the rings, and extend further outward from their pivots than inward from the same, in order that the water may keep their sharpened ends always in contact with the sides of the chutes, in order that they may thus be never in the water's way, and no orifice be ever opened when the gates are shut.

So long as there is water outside them, when closed, its own pressure keeps it outside, till the gates are opened by the action of the sliding rings.

The gates are convex as to the chutes, so as to avoid all angles except those they make at their outer ends with the chutes, which angles are rendered harmless by their position.

Everything about the inlet-passages is contrived to avoid all sorts of obstacles to the flow of water.

On the opening of the gates, they slide close alongside the chutes, so as to afford the amplest possible passages.

As long as there is water to flow, it preserves the amplitude of the passages by its pressure upon the gates thus drawn to one side.

The pivot-pins of all the gates have co-ordinate and conterminous motions, but each gate may have a motion of its own upon its pivot, and this peculiarity allows any gate to yield to an obstruction, without stopping the motion of the rings.

The contrivances herein described being entirely sufficient to the needs of the wheel, no curb is required.

Having thus described our invention,

What we claim as new, and desire to secure by Letters Patent, is—

The sliding rings a a', in combination with the fixed chutes b and the gates d, when the latter have a sliding motion in opening and closing the water-veins, and also an independent motion on their pivots, substantially as described.

JAS. D. BRYSON.
J. H. HARTSUFF.
